UNITED STATES PATENT OFFICE

2,590,673

VACUUM CLEANER FOR BARBER CHAIRS

Charles E. Bezanson, Malden, Mass.

Application March 8, 1948, Serial No. 13,626

3 Claims. (Cl. 155—188)

1

My present invention relates to vacuum sweeper equipment and more particularly to the combination of a vacuum sweeper and attachments for use with a barber chair.

The principal object of my invention is a barber chair vacuum sweeper attachment.

Another object is a vacuum sweeper and attachment for barber chairs which permits the chair to be raised and lowered without interfering with the operation of the vacuum sweeper.

Still another object is vacuum sweeper attachments for a barber chair which maintains the throat piece of the vacuum sweeper under the foot rest of the barber chair regardless of the movement of the chair, and

Other novel features comprising the construction and operation of my invention will appear as the description of the same progresses.

Referring more in detail to the drawings:

Fig. 1 is a fragmentary side elevation with my invention attached;

Fig. 2 is a fragmentary cross-section taken on the line 2—2 of Fig. 1, portions being broken away for convenience, and

Fig. 3 is fragmentary cross-section taken on the line 3—3 of Fig. 2 showing rotary electrical contact rings etc.

Referring more in detail to the drawings, 10 indicates a fixed pedestal of a barber chair and 11 indicates the movable portion which elevates and lowers the chair portion 12. Barber chairs are usually operated by hydraulic means which have been eliminated from the present drawings as having no bearing on the present invention. 13 indicates the foot rest of the chair which moves up or down and swings with the chair portion 12, dot-dash lines indicating an elevated position.

To the fixed pedestal portion 10 I have attached electrical contact rings the fixture comprising an outer shell which may be split at 15 and clamped together with bolts 16 or attached in any other suitable means. Within the shell 14 are located insulating rings 17 and 18. The insulating ring 17 is fixed against rotation in the shell 14 and has imbedded therein an electrical ring 19 of copper or other electrical conducting matter. The ring 19 is directly connected at 20 with an electric current supply source. Directly above the ring 19 is a similar ring 21 which is imbedded in the insulating ring 18 and in engagement with the conducting ring 19. Electric current is transmitted from the ring 21 through the conductor 22 to the vacuum cleaner 23. The throat piece 24 of the vacuum cleaner 23 is located under the foot rest 13 of the chair 12 and has a tube 25 extending up behind the supporting back 26 of the foot rest 13 and tightly engaged in member 27 fixed to the rotatable insulating ring 18. Telescoped in the throat member tube 25 is a slideable tube 28 which directly connects to the vacuum sweeper unit 23.

2

It will thus be seen that the chair 12 and attached vacuum unit 23 can be raised or lowered without raising or lowering the throat piece 24. At the same time the chair and vacuum unit 23 together with the throat piece 24 may be rotated and the electric contact ring 21 being in contact with ring 19 will supply electric current to the vacuum unit 23.

The throat piece 24 is adjusted to the proper height from the floor and remains there regardless of the position of the chair cleaning the floor as the chair is rotated from time to time.

While I have shown the apparatus in somewhat of a simplified form yet it is to be understood that I may vary the shape and construction of the parts within wide latitude while still remaining within the spirit of the appended claims.

Having thus described my invention what I claim as new is:

1. In a barber chair, a stationary base pedestal having a post vertically and rotatably adjustable in the base pedestal, a chair solidly supported at the upper end of the post, in combination with vacuum sweeper means secured to the under side of the chair, electrical conductor means for connecting the vacuum sweeper to a source of power, a suction inlet member constituting of a throat piece responsive to the vacuum sweeper to draw material therein, said throat piece being supported in a position of fixed vertical spacing relative to the bottom of the pedestal, and telescoping tubular connections located between the vacuum sweeper and the throat piece to provide for maintaining the latter member in its said fixed relationship to the bottom of the pedestal when the vacuum sweeper and chair are raised and lowered into various positions of adjustment in the said pedestal.

2. A device according to claim 1, in which the electrical conductor means includes a lower insulating ring fixed about the base pedestal and an upper insulating ring arranged for rotation relative to the lower insulating ring.

3. A structure according to claim 2, and further including supporting bracket means fixed on the upper insulating ring in a position to hold the throat piece in radially fixed relation to the axis of the pedestal in a raised position with respect to the bottom of this member in all positions of rotation of the chair about the pedestal.

CHARLES E. BEZANSON.
